UNITED STATES PATENT OFFICE.

JOSEPH M. COFFEY, OF NEW YORK, N. Y., ASSIGNOR TO CHAMBERS VALVE COMPANY,
OF NEW YORK, N. Y.

THROTTLE-VALVE-ACTUATING MECHANISM.

1,289,667.

Specification of Letters Patent. Patented Dec. 31, 1918.

Application filed July 5, 1917. Serial No. 178,824.

To all whom it may concern:

Be it known that I, JOSEPH M. COFFEY, a citizen of the United States, residing at New York, in the county of New York and State 5 of New York, have invented certain new and useful Improvements in Throttle-Valve-Actuating Mechanism, of which the following is a specification.

This invention relates to improvements in 10 throttle valve actuating mechanism particularly adapted for use on steam boilers of the locomotive type.

In order that a clearer understanding of 15 the present invention may be had, it is to be noted that the present invention is directed to the mechanism for actuating the throttle valve of a locomotive by the engineer from within the cab. This mechanism as herein-after described may be said to comprise 20 broadly an actuating shaft connected with the throttle valve proper for moving the same relatively to its seat, a crank on said shaft and a pull rod extending rearwardly from the crank to a point adjacent the back 25 head of the boiler where it is connected with the usual hand operated throttle lever. The boiler is, of course, exposed to relatively high temperatures or fluctuating temperatures of considerable magnitude while the tempera- 30 ture to which the pull rod is exposed, that is, the atmospheric temperature, is more nearly constant. There is, therefore, considerable difference in the relative expansion of these two elements under varying temperatures 35 which has a tendency to and frequently does, cause a gradual opening of the throttle valve to such an extent as to cause an unintentional starting of the locomotive with possible disastrous results. It is, therefore, one of the 40 objects of the present invention to overcome this principal objection, by so positioning, arranging and mounting the parts of the throttle valve actuating mechanism with respect to the boiler as to have all the ad- 45 vantages of former constructions without the attendant disadvantages, as above stated. A further object is to provide a simple and practical throttle valve actuating mechanism having relatively few parts which will be 50 inexpensive to manufacture and install. A further object is to provide a mechanism of the above character which may be easily and quickly assembled and disassembled as when repairing, cleaning or replacing worn parts.

Other objects will be in part obvious from 55 the annexed drawings and in part indicated in connection therewith by the following analysis of this invention.

This invention accordingly consists in the features of construction, combination of 60 parts and in the unique relations of the members and in the relative proportioning and disposition thereof; all as more completely outlined herein.

To enable others skilled in the art so fully 65 to comprehend the underlying features thereof that they may embody the same by the numerous modifications in structure and relation contemplated by this invention, drawings depicting a preferred form have been 70 annexed as a part of this disclosure, and in such drawings like characters of reference denote corresponding parts throughout all the views, of which:

Figures 1^a and 1^b together constitute a side 75 elevational view of the complete mechanism with certain parts in section or broken away in order that the construction and operation may be more clearly understood;

Fig. 2 is a vertical sectional elevational 80 view of a portion of the mechanism adjacent the steam dome; and

Fig. 3 is a plan view partly in section of a modified form of stuffing box.

Referring now to the drawings in detail 85 and particularly to Figs. 1^a and 1^b, 5 denotes a boiler of the locomotive type provided with a usual back head 6 and a steam dome 7 containing a throttle valve of any desired type. As this valve forms no direct part of 90 the present invention, it is believed to be unnecessary to illustrate and describe the same, except to state that it is provided with a main actuating shaft 8. This shaft 8 is inclosed within a sleeve 10 and projects 95 outwardly through the side of the steam dome 7 and into a stuffing box 11. A crank arm 12 is positioned at the end thereof and is pivotally connected with one link 13 of a pull rod which extends rearwardly to a 100 point adjacent the back head 6 where it is connected with a throttle lever 14.

These parts are so positioned and arranged as to cause the shaft 8 to turn in a counter-clockwise direction when the throttle lever 105 14 is moved toward the left, thus opening the throttle valve within the dome and allowing the steam to pass to the cylinders.

It is to be noted, however, that the pull rod preferably contains besides the link 13, connected with the crank arm 12, a relatively short link 15 pivotally connected thereto at 5 16, and also to a relatively long link 17 pivotally connected at 18. The opposite end of the main rod 17 has a threaded engagement 20 with a cylindrical member 21 adapted to slide in a bearing member 22. The 10 opposite end of the part 21 is pivotally connected at 23 with a relatively short link 24 which in turn is pivotally connected at 25 with the main throttle lever 14. This throttle lever is pivotally supported at 26 from an arm 27, projecting from the bearing member or bracket 22. A toothed segment 28 is also supported from the bracket 22 and is provided with a plurality of notches 30 on its under side and a drifting notch 31 on its 15 upper side, the latter being adapted to be engaged by a spring actuated dog 32 while the former is engaged by a spring actuated dog 33. The drifting notch dog which is spring actuated, will easily ride into and out of engagement with the notch 31 on movement of the throttle lever. The engineer can easily tell by the sense of touch when his throttle is in drifting position. The dog 33, however, is moved into and out 20 of engagement with the teeth 30 by the usual actuation of a latch lever 34.

Heretofore this throttle lever 14 and associated parts were rigidly mounted directly upon the back head of the boiler or closely 25 adjacent thereto. In the present case, however, they are slidably supported from a bracket 35. A tubular sleeve 36 is mounted in this bracket and has a threaded engagement at 37 with the member 38 bolted to the bearing member 22 for the rear end of the pull rod. The opposite end of this sleeve 36 also has a threaded engagement with a bracket 40, Fig. 1^b, rigidly mounted upon the stuffing box 11. The reactive thrust exerted 40 upon these parts on a leftward movement of the throttle lever is taken up entirely by this sleeve which is rigidly supported by the stuffing box upon the steam dome and any difference in relative expansion of the pull rod and associated parts and the boiler shell is taken up by the sliding connection of the sleeve 36 within the bracket 35.

The stuffing box shown in Fig. 1^b and Fig. 2 45 comprises the main body member 11 having a flange 41 through which bolts 42 are passed to engage tapped out recesses in the steam dome 7. About the sleeve 10 is mounted a curved or beveled adjusting member 43 which is wider at one side than at the other as appears in Fig. 3, whereby the stuffing box may be adjusted axially with respect to the opening in the steam dome through which the shaft 8 passes. As is well known, the steam dome is frequently of more or less

irregular curvature and the bearing member 65 43 permits the proper alignment of the stuffing box with respect to the opening regardless of its location. A nut 44 has a threaded engagement with the sleeve 10 and holds the bearing member 43 in place. 70

The right hand side of the stuffing box, as shown in Fig. 2, is provided with a chamber 45 having a cover 46 rigidly secured thereto by means of bolts 47. This cover member also contains a pocket 48 in which 75 rests one end of the shaft 8. As shown in Fig. 1^b the body member is provided with a lateral projection 40 through which the link 15 is adapted to pass. A gland containing packing material 50 further prevents 80 the escape of steam therethrough. This packing material is securely held in place by means of a member 51 fitting the link 15 and held in place by means of the bolts 52.

In Fig. 3, there is shown a slight modification. In this case, the stuffing box proper is substantially the same as shown in the co-pending application of Clark and Coffey, Serial Number 170,518, filed May 23, 1917, only that the outside end cover 53 is provided with a bracket 54 into which the sleeve 36 is threaded. The pull rod 17 passes through this sleeve and is connected at one end with a throttle lever as shown in Fig. 1^a, while its opposite end is again pivotally 95 connected directly to the crank arm 12.

While it is believed that the operation and method of use of this apparatus is clear from the above disclosure, it may be stated briefly that by releasing the latch lever 34 100 on the throttle lever 14 the spring dog 33 is drawn out of engagement and the throttle lever may be moved toward the left. This causes a gradual pull to be exerted upon the several parts of the pull rod 17 to cause 105 a movement of the same toward the left and consequently rotate the main shaft 8 in a counter-clockwise direction, and thus, open the throttle valve in the usual way. The entire reactive movement is taken up by the 110 sleeve 36 in which the pull rod 17 is mounted and finally absorbed by the stuffing box mounted upon the steam dome. Owing to the sliding support for the sleeve 36 and associated parts any difference in relative 115 expansion between the throttle actuating mechanism and the boiler may be considered as immaterial as it will have no effect upon the accidental closing or opening of the 120 throttle valve.

It is thus seen that the present invention provides a simple and practical throttle valve actuating mechanism which may be easily and quickly applied. The invention is therefore believed to accomplish, among 125 others, all of the objects and advantages herein set forth.

Without further analysis, the foregoing

will so fully reveal the gist of this invention that others can by applying current knowledge readily adapt it for various applications without omitting certain features that, 5 from the standpoint of the prior art, fairly constitute essential characteristics of the generic or specific aspects of this invention, and therefore such adaptations should and are intended to be comprehended within the 10 meaning and range of equivalency of the following claims.

I claim:

1. A throttle valve actuating rod adapted to extend from the steam dome to the rear of 15 the boiler, a throttle lever pivoted at one point to one end of said rod for actuating the throttle valve, a movable member associated with the rod to which said lever is also pivoted, and a fixed member on the 20 boiler in which said rod is slidably supported through said movable member whereby said pivot points may have a bodily movement with respect to the boiler under varying degrees of relative expansion and 25 contraction between the rod and boiler.

2. In combination with a steam boiler of the locomotive type, throttle valve actuating mechanism including a lever and rod, and supporting means upon the boiler permitting 30 relative movement between the actuating mechanism as a whole and the boiler due to different degrees of expansion or contraction thereof.

3. In combination with a steam boiler, a 35 fixed bracket thereon, a throttle valve actuating mechanism including a throttle lever pull rod and a bearing member for the lever on the pull rod, all slidably supported by said fixed bracket whereby said lever pull 40 rod and bearing member may have an equal relatively bodily movement with respect to said fixed bracket.

4. In combination with a steam boiler having a steam dome, a throttle valve actuating 45 mechanism including an actuating lever pull rod and a bearing member on said pull rod to which said actuating lever is pivotally connected and a fixed bracket on the boiler, said pull rod being supported by the steam 50 dome at one end and at its opposite end slidably resting in said fixed bracket whereby the pull rod actuating lever and bearing member may all move bodily with respect to the boiler when a difference in relative 55 contraction and expansion of the pull rod and boiler takes place.

5. In combination with a steam boiler of the locomotive type having a steam dome, a stuffing box on said dome, an actuating shaft 60 passing through said stuffing box, a crank arm on said shaft, a bracket mounted upon the rear part of the boiler, a sleeve supported by said bracket and stuffing box and having a loose connection with one of said parts to 65 permit relative movement due to difference

in expansion of said sleeve and boiler, and a pull rod mounted in said sleeve and connected with said crank arm.

6. In combination with a steam boiler of the locomotive type having a steam dome, a 70 throttle valve shaft passing through said dome, a stuffing box for said shaft, a crank arm on the shaft, a pull rod connected with the crank arm, a throttle lever connected with the pull rod, a bracket near the rear 75 end of said boiler, and a sleeve slidably mounted in said bracket and supported at its opposite end from said stuffing box, said sleeve being adapted to support said pull rod and transmit to the stuffing box the reactive 80 pressure of a pull exerted upon the throttle lever.

7. In combination with a steam boiler of the locomotive type having a steam dome, a 85 shaft passing out through said dome, a stuffing box for said shaft adjustably connected with said dome, a crank arm on the shaft, a pull rod connected with the crank arm extending toward the rear of the boiler, a stuffing box surrounding said pull rod adjacent its connection with the crank arm, a throttle lever connected with the pull rod, and means supporting said throttle lever from the boiler and permitting relative movement of said parts due to difference in 95 expansions.

8. In combination with a steam boiler of the locomotive type having a steam dome, a sleeve supported from the steam dome at one end, a bracket slidably supporting said sleeve 100 at the other end, a pull rod within said sleeve adapted to be connected with the throttle valve within the dome, and a throttle lever for actuating said pull rod.

9. In combination with a steam boiler of the locomotive type having a steam dome, a bracket near the back head of the boiler, a member extending between the bracket and dome and slidably supported at one end, a pull rod carried by said member adapted to 105 be connected with the throttle valve at one end, and a throttle lever and segment supported from said bracket.

10. In combination with a steam boiler of the locomotive type having a steam dome, 115 a support near the back head of the boiler, a member extending between said support and dome and slidably supported at one end, a pull rod carried by said member adapted to be connected with the throttle valve at one 120 end, and a throttle lever and segment supported from said member, said segment having a drifting notch on one side and a plurality of teeth upon the other and a latch lever on said throttle lever having dogs 125 adapted to coat with said notches.

11. In combination with a steam boiler of the locomotive type having a steam dome, a throttle valve actuating shaft, a sleeve surrounding said shaft, a stuffing box adjust- 130

ably connected with said dome, a pull rod connected with said shaft, a packing gland surrounding the pul rod adjacent the stuffing box, a supporting member surrounding said pull rod, a bracket slidably supporting said member near the rear end of the boiler, a bearing connected with said sleeve carrying a throttle lever and a segment, said throttle lever being pivotally connected with

10 a pull rod.

12. In combination with a steam boiler of the locomotive type having a steam dome, a throttle actuating shaft, a sleeve surrounding said shaft, a stuffing box adjustably connected with said dome, a pull rod connected with said shaft, a packing gland surrounding the pull rod adjacent the stuffing box, a sleeve surrounding said pull rod, a bracket slidably supporting said sleeve near the rear 20 end of the boiler, a member connected with said sleeve carrying a throttle lever and a segment, a drifting notch on said segment, a

plurality of teeth upon the opposite side of said segment, and spring actuated dogs adapted to coact with said notch and teeth. 25

13. In combination with a steam boiler, a steam dome having a throttle valve, a pull rod connected therewith for actuating the same, a fixed bracket on the boiler, a bearing member associated with the pull rod and 30 slidably supported in said fixed bearing, a throttle lever pivotally connected with said bearing member and said pull rod, and means whereby said lever may be locked in adjusted position with respect to said bearing member thereby to move freely with said pull rod in its contraction and expansion. 35

In testimony whereof I affix my signature in presence of two witnesses.

JOSEPH M. COFFEY.
